UNITED STATES PATENT OFFICE.

GEORGE R. FARRIS, OF STANBERRY, MISSOURI.

WIRE-STRETCHER.

1,342,625.

Specification of Letters Patent.

Patented June 8, 1920.

Application filed November 10, 1919. Serial No. 336,996.

To all whom it may concern:

Be it known that I, GEORGE R. FARRIS, a citizen of the United States, residing at Stanberry, in the county of Gentry, State of Missouri, have invented certain new and useful Improvements in Wire-Stretchers; and I do hereby declare the following to be a full, clear, and exact description of the invention, such as will enable others skilled 5 in the art to which it appertains to make and use the same.

This invention relates to wire stretchers and it has for its object to provide a construction that may be manufactured and 15 sold at a minimum cost and which furthermore will be most durable. Thus, not only will the first cost be little, but the cost of maintenance will be almost nothing. The greatest wear in the rack and lever type of 20 stretcher, is of course between the ratchets and their pivots and in the present construction, these pivots are so formed and arranged as to limit the wear entirely to the contacting surfaces of the pawls and pivots 25 while eliminating wear between the pivots and the operating lever.

A further object of the invention is to provide a simple and durable means for connecting the wire to be stretched, with a corresponding part of the stretcher.

In the drawings:

Figure 1 is an elevation showing the stretcher with the operating lever vertical, the rack bar being connected with the post 35 and the rock lever being connected with a wire to be stretched.

Fig. 2 is a vertical section on line 2—2 of Fig. 1.

Fig. 3 is a section on line 3—3 of Fig. 1 40 looking to the right.

Referring to the drawings the present stretcher comprises a bar 5 having rack teeth 6 and 7 on its opposite longitudinal edges and having attached to one end a 45 chain 8 which in practice is passed around a post or other support, and has a terminal hook for engagement with the chain between the bar and post to hold the bar to the latter.

50 In connection with the bar 5 there is employed a rock lever 9, having a handle 10 at one end while the other end is bifurcated with resultant spaced arms 11 and 12 between which the bar 5 is slidably received 55 with one set of rack teeth in the direction of

the handle 10 and the other in the direction of the free ends of the arms.

Between the arms 11 and 12 and at opposite sides of the bar 5, are disposed pawls 14 and 15, both of these pawls extending 60 from opposite edges of the arms 11 and 12 and having at one end the handles 17 and 18 respectively while at the opposite ends there are hooks 19 and 20 which latter are movable with the pawls into and out of engagement with the corresponding rack teeth 6 and 7. Through the hooked ends of the pawls are passed rods 21 and 22 respectively, having eyes at their ends with which are engaged the corresponding ends of helical springs 23 and 24, at opposite sides of the rack bar, these springs serving to hold the hook ends of the pawls normally and yieldably in engagement with the rack teeth. To hold the pawls pivotally between the 75 arms 11 and 12 a U bolt 25 is passed through the arms 11 and 12, with its bight or connecting portion against the arm 12, the arms of this U bolt pivotally engaging the pawls.

With the above described construction it 80 will be understood that as the lever 9 is rocked in the common plane of the pawls, the latter will climb along the rack bar 5 in one direction, the hooks alternately serving as a fulcrum block with the corresponding 85 U bolt arm as a fulcrum for the lever, to move the other pawl to the next tooth of its corresponding rack. During this operation, the helical springs insure the snapping of the hooks of the pawls into holding relation 90 to their corresponding rack teeth.

When it is desired to slide the rock lever to the opposite end of the rack bar, the handle portions 17 and 18 of the pawls are grasped and pressed toward each other, with 95 the result that the hooks are swung from the rack teeth and the portions of the pawls adjacent the hooks contact with the edges of the rack teeth, over which they may then be readily slid.

100 The wire to be stretched is connected with the rock lever through the medium of a rod 26 having an eye 27 at one end that engages an eye 28 connected with the lever arm 12. This rod passes slidably through guides 29 105 on the rack bar and beyond the end opposite to the chains referred to, the free end of the bar being provided with any desired type of wire engaging means.

110 It is found in practice, that by reason of

the use of the **U** bolt, the pivots of the pawls are prevented from spreading and also from rotating and in consequence, they do not wear the arms 11 and 12 of the rock lever.

5 The result is that the pawls have always their proper relation to the rack bar and the entire construction operates smoothly at all times. It will further be noted that the construction comprises extremely few 10 parts, each of which may be manufactured at a low cost and that the assembling of the parts is extremely simple and economical.

What is claimed is:

1. A wire stretcher comprising a rack bar 15 having means at one end for connecting it with a support, a bifurcated lever, between the furcations of which the rack bar is slidably received, a pawl between the furcations of the lever at each side of the rack bar, a **U** bolt passed through the furcations and 20 the pawls and on which the pawls are pivotally movable, means for holding the pawls yieldably in engagement with rack teeth of

the bar at corresponding edges of the latter and means for connecting with the lever, a wire to be stretched. 25

2. A wire stretcher comprising a bar having rack teeth at opposite longitudinal edges and having means at one end for connecting it with a support, a bifurcated lever between 30 the furcations of which the bar is slidably received, a pawl at each side of the rack bar between the furcations of the lever and having each a rod disposed through one end and having terminal eyes, helical springs 35 connecting the eyes of the pawls at opposite sides of the rack bar, a **U** bolt passed through the furcations of the lever and providing pivots for the pawls, and means for connecting with the lever, a wire to be stretched. 40

In testimony whereof I affix my signature in the presence of two witnesses.

GEORGE R. FARRIS.
